UNITED STATES PATENT OFFICE.

MAX SCHNEFEL, OF NEWARK, NEW JERSEY.

DESIGN FOR A CUTICLE KNIFE OR SIMILAR ARTICLE.

Application filed February 9, 1921. Serial No. 443,712. Term of patent 7 years.

To all whom it may concern:

Be it known that I, MAX SCHNEFEL, a citizen of the United States, residing at Newark, in the county of Essex and State of New Jersey, have invented a new, original, and ornamental Design for a Cuticle Knife or Similar Article, of which the following is a specification, reference being had to the accompanying drawings, forming a part thereof.

In said drawings, Figure 1 is a front view;

I claim:

The ornamental design for a cuticle knife or similar article as shown.

MAX SCHNEFEL.
